DESIGN.

M. E. GOLDBERGER.

BROOCH, BADGE, BUTTON, INSIGNIA, EMBLEM, PIN, OR SIMILAR ARTICLE OF MANUFACTURE.

APPLICATION FILED JAN. 17, 1919.

53,198.

Patented Apr. 15, 1919.

Inventor,
Melvin E. Goldberger

UNITED STATES PATENT OFFICE.

MELVIN E. GOLDBERGER, OF MILWAUKEE, WISCONSIN.

DESIGN FOR A BROOCH, BADGE, BUTTON, INSIGNIA, EMBLEM, PIN, OR SIMILAR ARTICLE OF MANUFACTURE.

53,198.

Specification for Design. Patented Apr. 15, 1919.

Application filed January 17, 1919. Serial No. 271,748. Term of patent 3½ years.

To all whom it may concern:

Be it known that I, MELVIN E. GOLDBERGER, a citizen of the United States, residing at Milwaukee, in the county of Milwaukee and State of Wisconsin, have invented a new, original, and ornamental Design for a Brooch, Badge, Button, Insignia, Emblem, Pin, or Similar Article of Manufacture, of which the following is a specification, reference being had to the accompanying drawing, forming part thereof.

The figure is a plan view of a badge, or similar article of manufacture showing my new design.

I claim:

The ornamental design for a brooch, badge, button, insignia, emblem, pin, or similar article of manufacture, as shown.

MELVIN E. GOLDBERGER,

Copies of this patent may be obtained for five cents each, by addressing the "Commissioner of Patents, Washington, D. C."
